UNITED STATES PATENT OFFICE.

ARTHUR T. MACE, OF CLEVELAND, OHIO, ASSIGNOR TO THE DOMESTIC ELECTRIC COMPANY, OF CLEVELAND, OHIO, A CORPORATION OF OHIO.

DRIVING MECHANISM FOR SEWING-MACHINES.

1,394,320.

Specification of Letters Patent.

Patented Oct. 18, 1921.

Application filed October 17, 1919. Serial No. 331,328.

To all whom it may concern:

Be it known that I, ARTHUR T. MACE, residing at Cleveland, in the county of Cuyahoga and State of Ohio, have invented a 5 certain new and useful Improvement in Driving Mechanisms for Sewing-Machines, of which the following is a full, clear, and exact description, reference being had to the accompanying drawings.

10 This invention relates to improvements in motor driven sewing machines, and has particular reference to a mechanism including a motor for incorporation in the heads of sewing machines for operatively connecting 15 and driving the upper or needle bar actuating means and the lower or shuttle actuating means.

The essential objects of this invention include a novel method of mounting a motor 20 within the usual standard sewing machine head and the arrangement of simple efficient gearing and connections for driving the upper and lower shafts actuating the needle and shuttle respectively.

25 In the provision of a driving motor within the standard head of a sewing machine certain limitations are imposed by the commercial requirements for such heads, the speed of a motor of the size adapted to enter 30 the head and capable of delivering the required power, and the requirement of directly connecting the upper and lower shafts in such manner that they shall be driven with precision in synchronism, and a more specific 35 object of this invention is to provide an arrangement of gearing which shall be more simple than that shown, described and claimed in my Patent No. 1,130,309, granted March 2, 1915, and which shall be still more 40 simple than the construction shown and described and claimed in my application No. 331,233 filed October 16, 1919, for driving mechanism for sewing machines.

My invention is hereinafter more fully described and is illustrated in the accompanying drawings. The essential characteristics of the invention are set forth in the claims.

In the drawings, Figure 1 is a front elevation of the head of a sewing machine embodying my invention, a portion of the head being shown in central vertical section; Fig. 2 is a horizontal section on the line 2—2 of Fig. 1; and Fig. 3 is a sectional detail showing the connection between the armature 55 shaft and the gear thereon.

In the drawings the usual sewing machine head is illustrated as having a bed plate 10, an upright standard portion 11 rising therefrom, and a horizontal arm 12 which carries the needle bar operating mechanism, the latter being omitted from the present drawings as it will be clearly understood, and needs no illustration. The usual needle bar operating shaft is illustrated at 13 and carries the hand wheel 14 while below the bed plate 60 10 and journaled in suitable brackets 16 is the shuttle operating shaft 17.

As clearly shown, the standard 11 of the machine is hollow and is the usual casting used in practically all modern sewing machines. I mount therein an electric motor 20 comprising the usual armature having a shaft 21 and field magnets, not shown. The motor may be suitably secured with its armature shaft in vertical position within the 75 head 11.

As previously set out I desire to provide a simple mechanism for connecting the armature shaft of a motor mounted vertically in the head with the upper and lower shafts, 80 which shall be commensurate with the commercial requirements of sewing machine head construction and of motor design, and which shall not necessitate increasing the size of the head or altering the shaft to accommodate 85 a motor of sufficient power. To illustrate the limitations imposed by commercial requirements, I may state that a motor capable of delivering the required power and small enough to enter the standard of the 90 head must run at the speed of at least 4,000 revolutions per minute, whereas the upper and lower shafts in the ordinary use of the sewing machine should not run materially over 1,000 revolutions per minute, and preferably should normally run much less while 95 delivering the full power of the motor. It will be seen then that to arrange direct gearing, I must provide for a reduction of at least 4 to 1 from the armature shaft to the 100 needle bar operating shaft and the shuttle operating shaft. To be commercially successful it is desirable that this reduction should be 4½ or 5 to 1. Other requirements are that this gearing shall be durable and 105 have teeth of sufficient size to deliver the required power without appreciable wear.

To accomplish these ends I have shown keyed to each of the projecting ends of the armature shaft, small bevel gears 22 and 23 110

which mesh with relatively large bevel gears 24 and 25, as large as the arm 12 permits and which may be integral with collars 26 and 27 secured to the shafts 17 and 13 respectively. The gears 22 and 23 are shown retained in position on the ends of the armature shaft 23 by suitable cap screws 28 having washers 29 overlapping the outer ends of the shaft 21 and gears 22 and 23. This 10 method of attachment of gears is illustrated as a practical means for providing a very small gear on the armature shaft without any undue expense in construction and assembling.

15 The requirement that the shafts 13 and 17 run at the same speed makes necessary the same ratio between the gears 22 and 24, and 23 and 25. Accordingly the gears on the armature shaft are preferably the same size, 20 and the gears with which they mesh are also preferably alike. The gear 24 is limited as to its external diameter by the internal cross sectional area of the head around the shaft 13, and accordingly I position the gear 24 25 beneath the spool holder 40, closing an opening in the casing, whereby I am enabled to slightly increase the size of this gear. It is equally desirable to make the gear 22 as small as possible in order that I may accomplish 30 the greatest possible speed reduction. By the construction shown I am enabled to make these gears in a practical fashion with a view to quantity production and provide gear teeth of a cross section capable of delivering the required power and adapted to 35 wear well.

Practice has demonstrated that a plain series motor may be used in this manner and that very satisfactory results in the 40 operation of a machine are accomplished by the using of this arrangement of gearing. The motor may be controlled through the usual foot or head operated rheostat. As is desirable, the power of the motor is increased when the machine slows down by reason of its use when sewing heavy fabric 45 or the like.

Having described my invention, I claim:

1. A standard sewing machine head, a 50 needle bar and shuttle actuating means suitably housed, an interconnecting hollow standard, an electric motor vertically mounted within said standard, and gears on the armature shaft of said motor in meshing engagement with corresponding gears on said needle bar and shuttle actuating means.

2. In a motor driven sewing machine having a standard head, a motor arranged within 60 said head, a shuttle actuating member beneath the bed plate of said machine, a needle bar actuating member within the horizontal arm of the machine, gears on said shuttle and needle bar actuating members in direct

engagement with gears on the projecting 65 ends of the armature shaft of said motor.

3. In the usual sewing machine head, an electric motor mounted within the upright standard, needle bar and shuttle actuating shafts extending from said standard, two 70 gears connecting one end of the armature shaft with the needle bar actuating shaft, and two gears connecting the other end of the armature shaft with the shuttle actuating shaft.

4. In the usual sewing machine head, an electric motor mounted within the hollow standard thereof, having a vertical armature shaft, bevel gears on the ends thereof in meshing engagement with bevel gears on 80 the needle bar and shuttle actuating shafts of said machine.

5. In the usual sewing machine head, a motor mounted within the upright standard thereof, two bevel gears connecting the 85 armature shaft with the needle bar actuating member of the machine, and two bevel gears connecting said shaft with the shuttle actuating member thereof.

6. In the usual sewing machine head, a 90 mechanism operating shaft therein, an electric motor mounted within the hollow upright portion thereof, a gear on the armature shaft of said motor in direct meshing engagement with a gear on said operating 95 shaft.

7. In the usual sewing machine head, operating shafts therein, an electric motor mounted within the hollow standard thereof, a vertical armature shaft therefor, small 100 equal sized pinions on said shaft, equal sized gears on said operating shafts in mesh with said pinions.

8. In a sewing machine having a standard head, needle bar and shuttle actuating shafts 105 therein, a motor mounted in the hollow portion between said shafts, large equal sized bevel gears on said shafts, and small equal sized bevel pinions on the armature shaft of said motor in mesh with said gears. 110

9. In the usual sewing machine head, a needle bar operating shaft therein, a shuttle operating shaft, a motor mounted within the hollow upright portion thereof, two pinions on the armature shaft of said motor, and a 115 gear on each of said operating shafts in mesh with said pinions, the size of said gears being limited only by the size of said head.

10. In the usual sewing machine head, having a needle bar operating shaft within 120 the horizontal arm and a shuttle actuating shaft within said head below the bed plate, a motor having an armature shaft mounted within the upright portion of said head, a bevel gear on said needle bar actuating 125 shaft as large as can be contained on said shaft within said head, a small bevel pinion on the armature shaft in mesh with said

gear, and a duplicate gear set between the armature shaft and said shuttle actuating shaft.

11. In the usual sewing machine head, having an opening in the horizontal arm thereof above the upright portion, a needle bar operating shaft within the horizontal arm, a shuttle actuating shaft within said head below the bed plate thereof, a motor having an armature shaft vertically mounted within the upright portion, a gear on

said needle bar actuating shaft as large as possible without projecting above said opening, a small pinion on the upper end of said armature shaft in mesh with said gear, and 15 a duplicate gear set between the lower end of the armature shaft and said shuttle actuating shaft.

In testimony whereof, I hereunto affix my signature.

ARTHUR T. MACE.
